(57) **CLAIM**

The ornamental design for a clamshell cooler, as shown and described.

DESCRIPTION

FIG. 1 is a top side view of a clamshell cooler showing my new design;

FIG. 2 is a top side view thereof, shown with the top door open;

FIG. 3 is an alternate top side view thereof;

FIG. 4 is a front top perspective view thereof;

FIG. 5 is a rear top perspective view thereof;

FIG. 6 is a left top perspective view shown in a closed configuration;

FIG. 7 is a front left top perspective view thereof;

FIG. 8 is front right top perspective view thereof;

FIG. 9 is a top perspective view thereof, shown with the lid in an open configuration;

FIG. 10 is an alternate top perspective view thereof;

FIG. 11 is a rear top perspective view shown in a closed configuration;

FIG. 12 is right side perspective view thereof;

FIG. 13 is an alternate right side perspective view thereof;

FIG. 14 is a top perspective view thereof, shown with the lid in an open configuration;

FIG. 15 is a bottom right perspective view shown in a closed configuration;

FIG. 16 is a bottom left perspective view thereof;

FIG. 17 is a bottom right perspective view thereof, with the stopper in an unplugged configuration; and,

FIG. 18 is a bottom side view thereof.
